PURIFICATION OF AROMATIC ACIDS USING
ZINC, ALUMINUM, OR MAGNESIUM

John J. Bredbeck and John B. Wilkes, Albany, Calif.,
assignors to California Research Corporation, San
Francisco, Calif., a corporation of Delaware
No Drawing. Filed Jan. 4, 1962, Ser. No. 164,374
11 Claims. (Cl. 260—558)

This invention relates to a novel method of improving the quality of dibasic aromatic acids. More particularly, this invention relates to a novel method of removing color bodies from said acids.

Aromatic dibasic acids are being increasingly used for preparing fine quality synthetic fibers as well as other polymeric materials. The demand for the dibasic acids has led to a variety of methods of synthesis of these acids. When the aromatic group is benzene, many of the routes use the analogous xylene as the precursor.

Among the methods of oxidizing the alkyl groups of the dialkylarenes is the use of aqueous sulfur type reagents. See, for example, W. G. Toland, *J. Am. Chem. Soc.*, 82, 1911 (1960). It has been found that the dibasic acids obtained by this method contain color forming impurities which make the acids unacceptable for a variety of applications, particularly, fine grade fibers. Even when the acid appears colorless, the products obtained therefrom may become discolored during formation or processing.

It has now been found that discoloring contaminants, which are present in the acid obtained by use of an aqueous sulfur type oxidant, where the oxidation is carried out in the presence of ammonia or ammonium ion, may be removed by treatment with zinc, magnesium, or aluminum metal. The impurities are thought to include some sulfur-containing compounds, but this invention is not intended to be limited to sulfur compounds, since the exact nature of the impurities is unknown.

The material treated with the metal is the "crude amide," rather than the acid. When using an aqueous sulfur-type oxidant in the presence of ammonia, the oxidate will usually contain as its major organic constituents diamide, monoamide and ammonium salts. The term "crude amide" is intended to define this product mixture.

The purification merely requires heating the crude amide with a small amount of zinc, magnesium or aluminum in the essential absence of air. A preferred method is to follow this treatment with a further treatment with a heavy metal salt. Activated carbon may be used in this invention either before, after or during the treatment with the metals and is found to enhance the purification.

After the treatment with the metals and metal cations, the metals may be removed and the solution hydrolyzed to the desired dibasic acid. While it is not known why these metals aid in the removal of color forming bodies, it would appear that the aluminum, magnesium and zinc act in a reductive manner.

The purification is operable for any dibasic acid obtained by oxidation of an aromatic hydrocarbon by an aqueous sulfur-type oxidant in the presence of ammonia, i.e., sulfur, sulfate, thiosulfate, bisulfite, etc. As examples of acid amides—by amides it is intended to include mono- and diamides and ammonium salts—the precursors to the dibasic acids, which are operable are the following: 1,4-naphthadioic amide, 1,6-naphthadioic amide, biphenyl-4,4-dicarboxylic amide, terephthalic amide, isophthalic amide, etc. While polynuclear aromatic dibasic acids may be used in this process, the mononuclear aromatic dibasic acids are preferred, i.e., phthalic, isophthalic and terephthalic, with particular preference for the latter two acids.

2

The zinc, magnesium and aluminum may be in any form. It is preferred that the metals be finely divided or powdered, for in this state the metal is most efficiently used. The amount of metal used may vary widely, amounts as little as 0.1 weight percent of potential acid values giving a demonstrable improvement. (By potential acid values is intended the total weight of materials which would give acid on hydrolysis. This includes amides, ammonium salts and the acid itself.) The amount of metal will usually depend on the degree to which the "crude amide" is contaminated and the desired quality of the product. While any amount of the metals may be used, amounts ordinarily will not exceed 20 weight percent of the potential acid values. Usually amounts in the range of 1 to 5 weight percent will be satisfactory. When very large amounts are employed, much of the metal remains unreacted, but with a great excess, a more rapid reaction is obtained.

Many of the common heavy metal soluble salts may be employed. The preferred metal cations are mercury, lead, cadmium and antimony. The amount of the salt is not critical and will usually be within the range of 0.1 to 10 weight percent of the potential acid values. The preferred range is 0.5 to 5 weight percent. Mixtures of the salts may be used. The anion may be any of the common anions such as the halides: chloride and bromide; acetate, sulfate, etc., as long as a water-soluble salt is obtained.

The temperature of the treatment with the metals as well as the metal cations will usually be at least 70° F. No advantage is obtained by increasing the temperature above 500° F. and temperatures in the range 160–250° F. have been found most practical from an operating standpoint and are preferred. The reaction time for the treatment with the metals will depend on their physical form, the rate of reaction increasing with increasing surface area. The metals in the powdered form are therefore preferred. The metals treatment will usually not be extended beyond a few hours and will generally be limited to less than two hours, times in the range of 1 minute to 1 hour having been found satisfactory.

Prolonged treatment with the heavy metal cations is also not required. A few minutes have been found practical and the time may vary from 1 minute to a few hours. The time period is one of expedience and is not critical.

While not essential to the purification, the use of activated carbon does enhance the final result. Any of the adsorbent forms of carbon may be used, e.g., activated charcoal. The carbon may be introduced prior or subsequent to the metals treatment and may be present during the metals treatment. Practical amounts of carbon have been found in the range 0.1 to 5 weight percent of the potential acid values.

The essential absence of oxygen is required during the treatment with metals. It has been found that if the crude amide is treated in the presence of air, little, if any, improvement occurs. While initially the color of the crude amide solution may diminish, the color rapidly returns. When only the metal treatment is used, oxygen must be excluded until the hydrolysis step. However, once the solution is carried through the treatment with the heavy metal salt, the presence of oxygen has no significant effect on the quality of the resulting dibasic acid. Nevertheless, for best results, it is preferred to continue to maintain the solution in an inert atmosphere, e.g., nitrogen, argon, hydrogen, etc., until the hydrolysis step.

The metal cations may be removed in a variety of ways, i.e., ion exchange resins, chelating agents, etc., the most practicable being precipitation with H₂S and then filtration. If hydrogen sulfide is used for removal, it is preferable to remove all of the hydrogen sulfide, prior to

hydrolysis of the amide. This may be conveniently done by stripping with, for example, steam, nitrogen, etc. Prior to the H_2S treatment, any excess metal may be removed by filtration.

The purification may be carried out batchwise or in a continuous manner.

The quality of the isophthalic acid has been correlated with the percent transmission of light through aqueous solutions of the sodium salts in the ultraviolet and visible range. Either the percent transmission may be determined at particular wave lengths, e.g., 3400 Å, or the percent transmission may be determined as the average of a narrow range of wave lengths by the use of filters. The latter may be reported as Tristimulus colors using a Lumetron Model 402E colorimeter. These methods help predict the quality of polymers obtained from the acid.

The following examples will serve to further illustrate the invention and are not intended as limitations.

Example I

Crude isophthalic amide (300 g.) (A)¹ was stirred with 2.4 g. carbon at 200° F. for 30 minutes. Throughout the metals and carbon treatment, the temperature was maintained at about 200° F. and the solutions were kept in an inert atmosphere of nitrogen. The solution was filtered and the filtrate slurried with 12 g. zinc and then stirred for 30 minutes.

The solution was then filtered removing the excess metal and 12 g. of mercuric chloride added, the mixture stirred for 5 minutes, and then filtered.

The metal cations were then precipitated out with hydrogen sulfide and the solution filtered. Excess hydrogen sulfide was removed by bubbling nitrogen through the hot solution. After the removal of the hydrogen sulfide, sulfuric acid was added to obtain a pH 2 and the solution heated at 420° F. for one hour to hydrolyze the amide. The solid which separated was filtered and washed at 100° F., slurried in 240 ml. of sodium bisulfate solution at 420° F. and heated for one hour to ensure complete hydrolysis. The acid was then filtered, washed and dried at 200° F.

The isophthalic acid obtained had a UV percent transmission: at 4000 Å. of 95.5; at 3400 Å. of 65.0.²

When 0.6 g. of lead acetate was used in place of the mercuric chloride using the above procedure, the isophthalic acid had a UV percent transmission: at 4000 Å. of 88.0; at 3400 Å. of 21.5.

When 0.6 g. of cadmium sulfate was used in place of mercuric chloride using the above procedure, the isophthalic acid had a UV percent transmission: at 4000 Å. of 88.0; at 3400 Å. of 14.0.

When no metals were used, using the same procedure, the isophthalic acid obtained had a UV percent transmission: at 4000 Å. of 83.4; at 3400 Å. of 0.0.

When 0.6 g. of antimony trichloride was used in place of mercuric chloride with isophthalic amide (B) using the above procedure, the isophthalic acid had a UV percent transmission: at 4000 Å. of 85.3; at 3400 Å. of 30.0

When the same procedure was carried out without the use of zinc and antimony with isophthalic amide (B), the isophthalic acid had a UV percent transmission: at 4000 Å. of 79.5; at 3400 Å. of 0.0.

Example II

Crude isophthalic amide (300 g.) (B) was slurried with 1.2 g. aluminum and heated for 30 minutes at 200° F. under nitrogen. Throughout the metals and carbon treatment, the temperature was maintained at about 200° F. and the solutions were kept in an inert atmosphere of nitrogen. The solution was filtered hot and 6 g. of mercuric chloride added and allowed to react for 5 min-

² All UV determinations were made in 0.5 M phthalic solution of 3 N sodium hydroxide in a 5 cm. cell.

utes and then hydrogen sulfide introduced to precipitate the metals.

The hydrogen sulfide was stripped off with nitrogen and 2.4 g. of carbon added, and the mixture stirred for 30 minutes. The solution was filtered and then subjected to hydrolysis as described in Example I.

The isophthalic acid had a UV percent transmission: at 4000 Å. of 93.2; at 3400 Å. of 44.0.

Example III

Crude isophthalic amide (300 g.) (C) was stirred with 2.4 g. carbon for 30 minutes. The temperature was maintained at 200° F. throughout the treatment with carbon and aluminum and the isophthalic amide was kept in an inert atmosphere of nitrogen. The solution was filtered and 0.6 g. of aluminum added and the mixture stirred for 60 minutes. Activated carbon (2.4 g.) was added and the mixture stirred for an additional 30 minutes, then filtered and subjected to the hydrolysis described in Example I.

The isophthalic acid had a UV percent transmission: at 4000 Å. of 91.2; at 3400 Å. of 15.0.

Isophthalic amide (C) treated without the aluminum according to the procedure of Example III had a UV percent transmission: at 4000 Å. of 83.3; at 3400 Å. of 0.0.

Example IV

Crude isophthalic amide (300 g.) (D) and activated carbon were mixed and stirred for 30 minutes. The temperature was maintained at 200° F. and the solutions were kept in an atmosphere of nitrogen throughout the treatment with magnesium and carbon. The carbon was filtered off and 0.6 g. of magnesium added, and the mixture stirred for 30 minutes. Activated carbon was then added and the mixture stirred for 30 minutes and filtered. The filtrate was then subjected to the hydrolysis treatment described in Example I.

The resulting acid had a Tristimulus percent transmission: blue, 87.5; green, 95.0; amber, 95.6. Acid obtained without magnesium treatment had Tristimulus percent transmission: blue, 82.2; green, 92.9; amber, 93.4.

Using the same procedure as Example IV with crude isophthalic amide (E) and 0.3 g. of zinc instead of magnesium, and also excluding the second carbon treatment, gave isophthalic acid having Tristimulus percent transmission: blue, 88.4; green, 94.9; amber, 95.2. Without the zinc treatment the acid had Tristimulus percent transmission: blue, 82.7; green, 91.4; amber 91.6.

As will be evident to those skilled in the art, various modifications of this process can be made or followed, in the light of the foregoing disclosure and discussion, without departing from the spirit or scope of the disclosure or from the scope of the following claims.

We claim:

1. In a process which comprises the preparation of mononuclear aromatic dibasic acids free of color-forming contaminants from mononuclear dialkyl arenes by contacting said arenes with an aqueous sulfur-type oxidant in the presence of ammonia to form a crude amide reaction product, the improvement which comprises contacting said crude amide with from 0.1 to 10 weight percent of the potential acid values of said crude amide with a member of the group consisting of zinc, aluminum and magnesium, at a temperature in excess of 70° F. and in the essential absence of oxygen.

2. A method according to claim 1 wherein the treatment with metals is followed with contacting the crude amide product with from 0.1 to 10 weight percent of the potential acid values of a member of the group consisting of mercury, lead, cadmium and antimony cations.

3. A method according to claim 1 wherein contact with activated carbon is included as an additional step.

4. A method according to claim 2 wherein contact with activated carbon is included as an additional step.

5. A method according to claim 2 wherein the metal

is zinc and the metal cation is mercury, and the treatment is carried out at a temperature in the range of about 160-250° F.

6. In a process which comprises the preparation of isophthalic acid free of color-forming contaminants from meta-xylene by contacting said meta-xylene with an aqueous sulfur-type oxidant selected from the group consisting of sulfur, sulfate, thiosulfate and bisulfite in the presence of ammonia to form a crude amide reaction product, the improvement which comprises contacting said crude amide with from 0.1 to 5 weight percent of the potential acid values of said crude amide with zinc at a temperature in excess of 70° F. in the essential absence of oxygen and then contacting the reaction product with mercuric cation.

7. A method according to claim 6 wherein aluminum is used in place of zinc.

8. A method according to claim 6 wherein magnesium is used in place of zinc.

9. A method according to claim 6 wherein the antimony cation is used in place of mercuric cation.

10. A method according to claim 6 wherein lead cation is used in place of mercuric cation.

11. A method according to claim 6 wherein cadmium cation is used in place of mercuric cation.
